US0D1087252S

(12) **United States Design Patent** (10) Patent No.: **US D1,087,252 S**
(45) Date of Patent: ** Aug. 5, 2025

(54) **FIGURINE**

(71) Applicant: **Melissa & Doug, LLC**, Wilton, CT (US)

(72) Inventors: **Beth Carretta**, Skillman, NJ (US); **Hали Jacobucci**, Monroeville, NJ (US); **Graham Wilson**, Denver, CO (US); **Sofia Dumery**, Westport, CT (US)

(73) Assignee: **Melissa & Doug, LLC**, Westport, CT (US)

(**) Term: **15 Years**

(21) Appl. No.: **29/883,325**

(22) Filed: **Jan. 26, 2023**

(51) LOC (15) Cl. **21-01**

(52) U.S. Cl.

USPC **D21/637**

(58) **Field of Classification Search**

USPC D11/160; D21/576, 578, 585, 621–623, D21/630–631, 634, 636–637, 658–661

CPC A63H 3/16; A63H 3/00

(57) **CLAIM**

The ornamental design for a figurine as shown and described.

DESCRIPTION

FIG. 1 is a front view of a figurine of the claimed design;

FIG. 2 is a right-side perspective view thereof;

FIG. 3 is a left-side perspective view thereof;

FIG. 4 is a right-side view thereof;

FIG. 5 is a left-side view thereof;

FIG. 6 is a rear view thereof;

FIG. 7 is a top view thereof; and,

FIG. 8 is a bottom view thereof.

The broken lines showing the figurine are for the purpose of illustrating portions of the article that form no part of the claimed design.

1 Claim, 8 Drawing Sheets
